CLAIM

The ornamental design for a pocket computer, as shown
and described.

DESCRIPTION

FIG. 1 is a top plan view of the pocket computer show-
ing our new design;

FIG. 2 is a bottom plan view thereof;

FIG. 3 is a front elevational view, the rear elevational
view being a mirror image thereof;

FIG. 4 is a right side elevational view thereof;

FIG. 5 is a left side elevational view thereof; and

FIG. 6 is a top, front, right side perspective view on an
enlarged scale.
